UNITED STATES PATENT OFFICE.

GEORGE T. JOHNSON AND HARRY W. STERTZBACH, OF COLUMBUS, OHIO, ASSIGNEES TO
THE BUCKEYE STEEL CASTINGS COMPANY, OF COLUMBUS, OHIO.

CAST CAR-TRUCK SIDE FRAME.

Application filed March 25, 1926. Serial No. 97,341.

This invention relates to car trucks and has special reference to cast side frames of the type shown in Letters-Patent No. 1,523,793, granted to H. W. Stertzbach and M. R. Hansen, January 20, 1925, in which the journal box is integral with tension and compression members which have the form of inverted channels. The object of the present invention is to provide a construction which will connect the side walls of the compression chamber in the region of the journal box and overcome the tendency to buckle under the compression and shearing stresses. The invention is illustrated in the accompanying drawing and will be hereinafter fully described and particularly defined.

In the accompanying drawing;

Figure 1 is a side elevation of a portion of a side frame embodying the present invention;

Figure 2 is a top plan view of the same; Figure 3 is a section on the line 3—3 of Figure 2;

Figure 4 is a detail section on the line 4—4 of Fig. 1.

The side frame comprises a column 1, a journal box 2, a compression member 3, and a tension member 4 connecting the upper and lower ends respectively of the column with the top of the journal box. The tension member is in the form of an inverted channel, the top plate of same lying in an inclined plane extending from the bottom of the column to the upper inner corner of the journal box. The compression member is only in the form of an inverted channel between the columns and its plate 6 instead of following the plane of the top edges of the side walls, extends obliquely from the top of the frame at the top of the column to the inner upper corner of the journal box to which it is united close to the junction of the journal box and the tension member.

Approximately over the center of the journal box, a bridge 7 unites the side walls of the compression member and prevents them from buckling under vertical load and causes

them to act efficiently under transverse load.

It will be noted that the plates of the compression and tension members are united with the journal box at substantially the same point and also serve to unite the side walls or flanges in the region so that the compression and shearing stresses will be effectually met and buckling avoided. The side walls are connected by metal which is an essential element of the structure and not by a mere accessory having only the functions of a tie.

Having fully described our invention what we claim as new and desire to secure by Letters-Patent, is:—

1. A cast side frame for car trucks having a column, a journal box, a compression member, and a tension member, the plate of the tension member being at the top of the same and united with the journal box at the inner corner thereof and the plate of the compression member extending obliquely with respect to its sides from a point over the column to the journal box and united with the box approximately at the junction of the tension member therewith.

2. A cast side frame for car trucks including an integral journal box, and a compression member, comprising a plate and side walls integrally united with the journal box, the plate being disposed obliquely with respect to the edges of the side walls and uniting the side walls in the region of said integral journal box.

3. A cast side frame for car trucks including an integral journal box, a compression member comprising a transverse plate and side walls all integrally united with the top of the integral journal box, the plate being disposed obliquely with respect to the edges of the side walls and uniting said walls, and a bridge uniting the upper edges of the walls above the journal box.

In testimony whereof, we have signed this specification.

GEORGE T. JOHNSON.
HARRY W. STERTZBACH.
